FIG. 4.

UNITED STATES PATENT OFFICE.

ELMER L. ADAMS, OF GRANITE, OKLAHOMA.

CURRYCOME.

1,135,482.

Specification of Letters Patent. Patented Apr. 13, 1915.

Application filed March 8, 1912. Serial No. 682,416.

To all whom it may concern:

Be it known that I, ELMER L. ADAMS, a citizen of the United States, residing at Granite, in the county of Greer, State of Oklahoma, have invented certain new and useful Improvements in Currycombs; and I do hereby declare the following to be a full, clear, and exact description of the invention, such as will enable others skilled in the art to which it appertains to make and use the same.

This invention relates to improvements in self-cleaning curry combs.

The principal object of the invention is to provide a curry comb in which means are provided for automatically cleaning the teeth thereof whenever the operator's grasp is released.

Another object of the invention is to provide a curry comb having a cleaner attachment for the teeth which normally protects the teeth of the comb from becoming damaged.

A further object of the invention is to provide a curry comb having a cleaner plate associated therewith and yieldingly forced outwardly by springs, and a handle lever of novel construction fulcrumed upon the back of the comb and engageable with the cleaner plate to shift the latter against the tension of the springs.

A still further object of the invention is to provide a curry comb of the character described, which is composed of a minimum number of parts, is simple in construction, and is cheap to manufacture.

With these and other objects in view, the invention consists in the construction and novel combination of parts hereinafter fully described, illustrated in the accompanying drawings, and pointed out in the claim hereunto appended; it being understood that various changes in the form, proportion, size and minor details of construction within the scope of the claim may be resorted to without departing from the spirit or sacrificing any of the advantages of the invention.

In the drawings: Figure 1 is a top plan view of a curry comb constructed in accordance with my invention. Fig. 2 is a bottom plan view thereof, Fig. 3 is a side elevation of the same, Fig. 4 is a detail longitudinal sectional view through such a comb, Fig. 5 is a transverse sectional view taken on the line 5—5 of Fig. 2, Fig. 6 is a perspective view of one of

the comb plates, and Fig. 7 is a perspective view of the cleaner plate.

Like reference numerals designate corresponding parts in all the figures of the drawings.

Referring to the drawings, the invention comprises a back plate 5 from which a handle 6 rearwardly projects.

Secured to the underside of the plate 5 is a plurality of transversely disposed comb plates 7. These plates are formed of metal, and are bent into U-shaped formation, the bight portions 8 thereof being secured to the plate 5 by rivets or other suitable fastening means. The legs or walls 9—9 of each plate 7 are each recessed at its outer lower ends, as indicated by the reference numerals 10 to form resultant tongues 11, the tongues of the comb plates being arranged in alinement, and each formed with a series of teeth 11^a.

My invention further comprises a cleaner plate 12 which is formed of sheet metal and corrugated to form resultant ribs 13 and channels 14. The channels are alternately disposed between the walls 11 of the comb plate 7 and between the respective comb plates, the walls 9 of the plates fitting into the ribs 13. The tongues 11 of the plates project through elongated openings 15 which are centrally formed in the ribs 13. The openings 15 are of such widths as to freely receive the teeth 11^a of the comb plate 7, and as a result, when said cleaner plate is moved downwardly, the side edges of the opening will scrape the walls of the teeth 11^a and thereby free the same from any dirt.

In order to normally retain the cleaner plate 12 in spaced relation to the back plate 5 and in such a position as to have the ribs 13 constitute guards for the teeth 11^a, there is provided a plurality of flat springs 16 which are disposed between the cleaner plate and the back plate. These springs are preferably arranged within the respective comb plates 7, and are centrally secured thereto, the free ends thereof projecting downwardly and bearing against the cleaner plate 12. The cleaner plate 12 projects beyond the respective ends of the comb plates and a strengthening bar 17 is secured to each end of the cleaning plate beyond the comb plates.

In order to retract the cleaner plate against the tension of the springs, there is provided a handle lever 18 which is preferably formed from a single piece of stout

wire. This wire is centrally bent to form a loop constituting a handle 19 which is normally disposed directly above and in spaced relation to the handle 6. The end portions 5 of the wire are then twisted together and downwardly bent and then respectively diverge outwardly, as indicated at 20—20, to form a fulcrum for said handle lever. The wire thence extends forwardly, and is bent 10 to form a compound curve, each curve being indicated by the reference numeral 22. The extreme end portions of the wire are then bent outwardly, as indicated at 23—23 and thence downwardly, as at 24—24, the last 15 mentioned portions fitting within the grooves 25—25 formed in the side edges of the back plate 5. The extreme end portions are then bent inwardly to form resultant fingers 26—26 which respectively engage under the 20 central channel 14 of the cleaner plate 12. It will thus be observed that when the operator grasps the handle 6 and loop 19 of the handle lever, the fingers 26 of said lever will be caused to engage the cleaner plate 25 and elevate the same against the tension of the spring. The curry comb can then be used, and after the operation has been complete, the cleaner plate will be returned to 30 its normal position as soon as the operator releases his hold, said return movement of the cleaner plate cleaning the teeth 11^a as above described.

What is claimed is:

35 In a curry comb, the combination with a back plate, provided with a handle of a plurality of spaced comb plates secured

thereto, a cleaner plate engageable with the comb plates said cleaner plate being corrugated to form resultant ribs and channels said channels respectively fitting between 40 adjacent comb plates and the ribs, said channels being formed with openings for receiving the outer ends of the comb plates, the channel portions bearing against the comb plates for the greater portion of their length 45 whereby said plates are supported from bending, springs disposed between the back plate and the cleaner plate for yieldingly holding the latter outwardly to guard said comb plates, said cleaner plate projecting 50 beyond the respective ends of the comb plates, a strengthening bar secured to each end of the cleaner plate beyond the comb plates and a rearwardly projecting forked lever normally in contact with the top of 55 said back plate engaging oppositely disposed notches midway of said plate, fingers formed with the extremities of said forks engaging the central channel of the cleaner plate, a rearwardly projecting angular arm 60 formed with said lever upwardly parallel with the handle, adapted on the depression of said arm to rock said lever on said back plate and to actuate the cleaner plate against the tension of the spring for removing waste 65 matter from the comb plate.

In testimony whereof, I affix my signature, in presence of two witnesses.

ELMER L. ADAMS.
